UNITED STATES PATENT OFFICE.

DANIEL H. CLOSE, OF KEYPORT, NEW JERSEY.

BURGLAR LOCK FOR REVOLVING DOORS.

Application filed December 14, 1920. Serial No. 430,644.

To all whom it may concern:

Be it known that I, DANIEL H. CLOSE, a citizen of the United States, residing at Keyport, in the county of Monmouth and 5 the State of New Jersey, have invented certain new and useful Improvements in Burglar Locks for Revolving Doors, of which the following is a specification.

This invention relates to a protective device for banks, trust companies, jewelers, etc. the object of the device being to entrap in the building, bank or store, any person or persons attempting to rob or hold up employees or other persons entrusted with 15 money or valuables kept within said building. In all modern building of this type it is the present custom to employ a revolving door which permits entrance and exit as long as the door is free to revolve. Usually 20 these doors are not provided with any locking means as they are generally used as storm or weather doors, being often removed during the summer months, or folded back so as to be out of the way. The 25 present invention contemplates the locking of said door through electrical means from one or more places located within the building, the door when so locked remaining in locked condition during a certain period of 30 time regulated by the running of a clock mechanism with which is combined a disc normally covering a key-hole but uncovering said key-hole at certain definite intervals of time, as for example every fifteen 35 minutes, the locking means being releasable only during alignment of a key-hole in the disc with one in the door of the lock containing casing.

With this general statement of the object 40 of the invention the details of construction will be readily understood as shown in the accompanying drawings, in which:

Figure 1 is a top plan view of the door, the wall of the building adjacent the entrance being shown in section.

Figure 2 is an elevation of the upper inner portion of the door, parts being broken away and in section.

Figure 3 is an enlarged detail sectional view showing the bolt holding and releasing means.

Figure 4 is a section on the line 4—4 of Fig. 2.

Figure 5 is a rear face view of a key-hole 55 guard or disc.

In the drawings A designates the vesti-

bule or approach to the door and B the entrance way into the building, flanked by the usual curved partitions C employed with doors of the revolving type. In the entrance B is placed the door 1 braced as at 2 and provided with bars or other form of grating 3. On the top of the door, supported on its wings, I place a steel band 4, perforated as at 5 and provided with a number 65 of stop blocks 6.

Above the door and supported on the partitions C is a steel box or casing 7, the inner side of which is hinged to swing open and give access to the interior, but normally locked. Within this case are one or more bolts 8 having each a collar 8^a and adapted to be forced downwardly by a coil spring 9, bearing against a partition 10 and the collar, respectively, the bolt being 75 mounted to work in the partition and in and through the bottom of the casing.

Electro-magnets 11 are placed adjacent each bolt, and are provided with armatures, 12 having stems 13 that normally engage 80 the underside of the collars 8^a and hold the bolts from engagement with the band 4. In practice a bolt will be arranged on opposite sides of the door, an electromagnet being placed in the casing above each 85 of the partitions C, but the device might be operated with one bolt only if desired.

An electric circuit normally open but adapted to be controlled by a switch E controls the magnets. In practice the switch 90 will be of the push button type, and the circuit may be arranged so that it may be closed at two or more points in the building.

The casing is provided with key-hole 7^a 95 any form of lock being used, and on the inner face of the casing is placed a disc 14 normally covering the key-hole 7^a, but provided with a number of slots 15, preferably about four in number, adapted to align successively with the key-hole on rotation of the disc.

A clock 16 is mounted in the casing 7 and on its rear face carries a wheel 17 making one complete rotation each hour. A 105 similar wheel is fixed on the disc shaft as at 18 and a belt or chain 19 connects the two wheels. This gives the disc a rotation once each hour, and if there are four slots 15 the key-hole 7^a will be uncovered each fifteen 110 minutes. This disc may rotate continuously with the clock or the latter may be started

electrically, being put into the circuit D, in which case the face or dial would be dispensed with, and the disc 14 would start to rotate only on closing of the circuit D and it would be fifteen minutes from the time the circuit was closed before the casing 4 could be opened and the bolts 8 lifted, this last operation being performed by hand.

The operation may be briefly summed up 10 as follows:—If any attempt is made to hold up the employees, or other persons in the building the closing of the circuit D by merely pressing a button will retract the armatures 13 and allow the bolts 8 to spring 15 into engagement with the band 4. If a bolt should fail to enter one of the openings 3 it would still fall sufficiently to lie in the path of the perpendicular end of the lug 6 nearest the opening missed by the bolt and 20 would be struck by said end of the lug, as indicated in Figure 3, and further rotation of the door would be stopped until the bolt had been lifted to allow the lug to pass 25 under it, it being understood that the door is so mounted as to rotate in one direction only.

The door cannot therefore be revolved to 30 permit any one to leave the building until the disc 14 comes into such position that one of the slots 15 will register with a keyhole in the casing. Only during registration of a slot 15 with the keyhole 7^a can access to 35 the casing be had to unlock the door 1.

This will give ample time to telephone or 40 otherwise signal the proper authorities and for assistance to arrive.

In the case of a bank the mere fact that 45 the door had been locked during banking hours would of itself spread an alarm even if those inside were prevented from giving one.

From the drawing and the above descrip-

tion it is thought that the invention will be clearly understood.

I do not wish to be limited to any particular clock device and have not therefore described in details the clock mechanism as it does not form a part of this invention.

What I claim is:—

1. The combination with a revolving door, 50 a metal band carried by the door top and suitably perforated, bolts adapted to drop into said perforations, an electromagnet for each bolt having an armature normally holding the bolt in elevated position, a normally open circuit in which said magnets are placed, and time controlled means controlling access to said bolts.

2. The combination with a revolving door, 55 a metal plate carried by the door top and having bolt engaging means, a casing arranged above the door and having a hinged side member normally locked, bolts arranged in the casing and adapted to work through the casing bottom and engage said plate, and 60 a clock mechanism in the casing and controlling the period of time during which the casing may be unlocked.

3. The combination with a revolving door, 65 of a casing placed above the door, door locking means arranged partly on the top of the door and in said casing, electro-magnetic means for controlling locking of the door, said casing having a hinged and normally locked member giving access when in open 70 position to the casing for resetting the locking means, said hinged member having a key-hole therein, a disc in the casing normally covering said key-hole, and having 75 slots adapted to successively register with the keyhole, and a clock mechanism for rotating said disc.

In testimony whereof I affix my signature.

DANIEL H. CLOSE.
